UNITED STATES PATENT OFFICE.

ERNEST C. MUSSER AND THEODORE DILGER, OF BLUEFIELD, WEST VIRGINIA.

HAND-REAMER.

1,126,649.

Specification of Letters Patent.

Patented Jan. 26, 1915.

Application filed June 22, 1914. Serial No. 846,675.

To all whom it may concern:

Be it known that we, ERNEST C. MUSSER and THEODORE DILGER, citizens of the United States, residing at Bluefield, in the county of Mercer, State of West Virginia, have invented a new and useful Hand-Reamer, of which the following is a specification.

This invention relates to a hand reamer and more particularly to one which is especially adapted to ream watch bezels.

The invention aims to provide a reamer which is rotated by hand and may be easily and quickly adjusted to thus ream a watch bezel to the desired size for the reception of a crystal.

A further object is to provide a hand reamer with cutters which may be adjusted during the manual rotation of the reamer.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the drawings accompanying this specification and forming a part thereof, the preferred embodiment of our invention has been illustrated, in which:—

Figure 1 is a view in elevation of our improved hand reamer, illustrating the same in the act of reaming a watch bezel, the latter being fragmentally depicted. Fig. 2 is a view in longitudinal section of the reamer. Fig. 3 is a bottom plan view thereof. Fig. 4 is a cross sectional view taken on the line 4—4 of Fig. 2. Fig. 5 is a detail view in perspective of one of the movable cutters.

Referring to the drawings in which similar reference numerals designate corresponding parts throughout the several views, the handle 7 is enlarged at its lower extremity to form the head 8.

A central bore 9 extends for a limited distance within the head and communicating with which are the three symmetrically arranged and radially extending slots 10.

The slots 10 are adapted to receive the cutters 11 therein and the bore 9 is adapted to receive the expanding member 15 therein. The bore 9 extends a slight distance between

the lower level of the slots 10 and communicates with the threaded bore 13 which extends entirely through the handle or shank 7. The expanding member includes a conical lower portion 14 and an upper cylindrical portion 15, the latter being of such size as to slide within and be guided by the side walls of the bore 9.

A thumb screw 16 threadedly engages the bore 13 and is provided with the lower restricted portion 17 which contacts with the expanding member and is adapted to move the same in a forced manner. The upper extremity of the thumb screw is provided with the knurled head 18 by means of which the cutters may be adjusted during the manual rotation of the reamer. The three cutters are exactly similar, for which reason, only one will be treated in detail, which as illustrated in Fig. 5, comprises the body portion 19 and the lower and more restricted portion 20. The difference in size between the portions 19 and 20 defines two shoulders or ledges 21 by means of which the cutters are held within the slots 10.

Three segmental plates 23 are rigidly secured to the cutter head by the screws 24 or allied means and which plates are spaced a distance apart so as to define three slots 25 which lie directly above but are more limited in width than the slots 10. The slots 25 are of such size as to slidably receive the portion 20 of the cutters therein but too restricted to allow the portion 19 of the cutters to pass therethrough. This provides that when the cutters are mounted within the slots and the plates 23 secured to the cutter head, the cutters may move freely longitudinally in the slots but are prevented from moving transversely thereof. The cutters are each provided with the cutting blades 26 rigidly secured thereto, which cutting blades include the serrated or cutting edges 27. The adjacent central portions of the segmental plates 23 are rounded as at 28, which allows portions of the helical expanding member to pass therethrough but prevents the same from becoming entirely detached from the head. Each of the cutters is provided with the groove 29 extending along the upper surface, which groove is adapted to receive the compression spring 30 therein, which spring contacts with the rear wall 31 of the groove.

A band or ring 32 extends around the head 8 and fits within the annular groove or

ledge 23 so that the outer surfaces of the ring and head will lie substantially in the same plane to thus define a continuous and unbroken surface. The ring 32 includes 5 three upstanding ears 34 which extend in front of the slot as illustrated in Fig. 2 and receive the compression spring 30 thereagainst. This confines the compression spring within the groove 29 and a similar 10 groove 35 which is formed along the bottom wall of the slots 10. The inner edge of each cutter is provided with the beveled face 22 which receives the conical surface of the expanding member thereagainst and provides for the forced adjustment of the cutters. The surface 36 of the handle or shank 7 is serrated or knurled so as to provide a suitable grip, by means of which the reamer may be manually rotated. The head of the 15 thumb screw extends upwardly within the palm of the hand and this provides for either the expansion or retraction of the various cutters, while the reamer is being rotated. The reamer thus formed is particularly adapted for reaming watch bezels. It 20 has been found in practice that the watch crystals vary in size, necessitating the reaming of the watch bezels. This can be quickly and conveniently accomplished with the 25 30 reamer as herein described.

Having thus fully described our invention, what we claim is:—

A manually operable reamer for watch bezels comprising a head, a handle projecting therefrom, a bore extending through 35 said head and handle and enlarged for a limited distance within said head, an expanding member positioned in the enlarged portion of said bore, segmental plates secured to the said head and positioned a distance apart, defining slots, said head provided with slots registering with and slightly larger than the slots defined by said plates, cutters slidably mounted within and limited to rectilinear motion by said slots, said head 40 and cutters provided with registering grooves, springs positioned within said grooves adapted to retract said cutters, and a ring frictionally engaging the head and provided with downwardly extending ears 45 50 extending in front of the cutter grooves and maintaining the same within said head slots.

In testimony that we claim the foregoing as our own, we have hereto affixed our signatures in the presence of two witnesses.

ERNEST C. MUSSER.
THEODORE DILGER.
